Frederick R. Parker

UNITED STATES PATENT OFFICE.

FREDERICK R. PARKER, OF CHICAGO, ILLINOIS.

TEST-CONNECTOR.

1,122,028.

Specification of Letters Patent. Patented Dec. 22, 1914.

Application filed November 30, 1906, Serial No. 345,788. Renewed December 30, 1913. Serial No. 809,589.

To all whom it may concern:

Be it known that I, FREDERICK R. PARKER, a citizen of the United States of America, residing at Chicago, in the county of Cook and State of Illinois, have invented a new and useful Test-Connector, of which the following is a specification, reference being had to the accompanying drawings, illustrating same.

10 My invention relates in general to devices for clamping wires, strands or conductors therein, the form herein specifically described being more particularly adapted to clamp two or more wires or conductors in 15 electrical conductivity with each other. It may however be employed in various places where clamps or connectors of various kinds are used.

The principal objects of my invention are, 20 to provide a clamp or connector for wires, strands or conductors, constructed so that one or more wires may be loosened and removed therefrom while another wire (or wires) remains clamped in the connector; 25 and to provide compactness and simplicity of construction in such a device.

Other objects will be apparent from the following specification.

In such devices, usually termed "test connectors," used on telephone, telegraph or other lines, to clamp two wires in conductive relation with each other, it has been necessary heretofore to loosen both of the wires in the connector when it was desired 35 to remove only one therefrom. This causes great inconvenience in the use of such devices, principally due to having to handle the various parts and to the fact that the lineman so often drops the connector to the 40 ground from a pole and is compelled to climb down the pole to get it. To avoid dropping it he generally has to remove one wire therefrom and then tighten the connector onto the other wire, or remove it 45 from both wires and put it into his pocket while testing the line. Also, with such connectors it is necessary to hold both wires and the connector, while adjusting both wires simultaneously in the connector, and 50 at the same time tighten the bolts and nuts to clamp the wires in place, all of which is very hard for one man to do.

My present invention provides a connector from which one wire may be removed 55 while the other wire of the two is held

clamped tightly therein, thus doing away with the inconveniences above mentioned. Also, in my connector, it is only necessary to hold and clamp one wire at a time in the connector, which can be readily done. 60 The advantages of such a connector can be readily seen.

In the accompanying drawings illustrating the preferred forms of my invention,— Figure 1 is a plan view of a two-bolt connector, with a pair of wires clamped therein; Fig. 2 is an end view of Fig. 1, with the wires removed therefrom; Fig. 3 is an end view of a connector constructed to accommodate and clamp four wires therein; 70 and Fig. 4 is an end view of a modified form of the connector shown in Fig. 2.

Like characters refer to like parts in the several figures.

In Figs. 1 and 2, 1 is a plate, preferably made of copper, through which bolts 2 2 are threaded as shown at 16. The plate 1 is preferably provided with V-shaped grooves 3 3 thereacross near one edge thereof. Plates 4 4, preferably formed out of sheet copper, are placed loosely upon bolts 2 2, on opposite sides of plate 1, each plate 4 being provided with a V-shaped groove 7 thereacross to register with a groove 3 in plate 1. Nuts 5 5 are threaded onto one end 85 of bolts 2 2 to hold one plate 4 in place, and nuts 6 6 are threaded onto the other ends of bolts 2 2 to hold the other plate 4 in place. Each plate 4 is preferably provided with a turned edge 8 adapted to bear against 90 plate 1.

When the connector is placed in service, wire 9 is placed in one pair of grooves 3 and 7, and nuts 5 5 are screwed down to clamp wire 9 in place between plate 1 and a plate 4. Then the other wire 10 is placed in the other pair of grooves 3 and 7, and nuts 6 6 are screwed down to clamp wire 10 in place between plate 1 and the other plate 4. 95

When it is desired to remove one of the wires 9 or 10 from the connector, one pair of nuts 5 5, or 6 6, is loosened and the corresponding wire removed, the other wire remaining tightly clamped in the connector, due to the bolts 2 2 being threaded through the middle plate 1. It will be readily seen that it is immaterial which one of the wires 9 or 10 is removed. It will also be understood that both of the wires 9 and 10 may be removed if desired, by loosening 110

all of the nuts 5 5 and 6 6. Wires 9 and 10 may be of different sizes.

In Fig. 3 the middle plate 11 is provided with four V-shaped grooves and the outer plates 12 12 each with two grooves, for clamping four wires in the connector. With this construction two of the four wires may be removed and the other two held tightly clamped. If it is desired, only three wires 10 may be clamped in the connector, the remaining space being left vacant. When three wires are used, either one or two may be removed at one time.

It will be readily seen that only two wires 15 may be clamped in the connector of Fig. 3, and, if desired, their ends may be bent back to fill the remaining two spaces for the wires. This gives a bearing surface for each wire double that provided in other test connectors now in use.

In Fig. 4 the bolts 2 2 are each provided with a central nut 13 placed within a springy piece of sheet metal 14 formed preferably as shown. Outside of the portion 14 25 is placed another springy piece of sheet metal 15 formed preferably as shown. When the nuts 5 5 and 6 6 are screwed down, the wires are clamped between the free ends of the portions 14 and 15 much 30 the same as in Fig. 2.

The nuts 5 5 and 6 6 may be wing nuts if desired. One pair of nuts 5 5 or 6 6 for each bolt 2 may also be replaced by a head on the bolt.

35 If desired, the connectors may be made with but one bolt 2 instead of two.

All of the clamping or jaw portions may be made of any suitable material. For copper wire I preferably use copper, and for iron wire I preferably use copper electro-galvanized. Brass, bronze, aluminum or iron may be used for these parts for various 40 conditions and requirements.

It will be readily seen that the several 45 wires to be clamped in a connector may be of various sizes.

If desired, each bolt 2 may be permanently secured to the middle plate 1 or 11, or made in one piece therewith.

50 I do not wish to limit this invention to the particular details of construction as illustrated, nor to the materials specified, as many modifications may be made therein without departing from the scope of the 55 appended claims.

What I claim as my invention and desire to secure by Letters Patent is,—

1. In a connector comprising an intermediate member, a screw member extending therethrough, spring metal clamping plates 60 mounted on the screw member on opposite sides of the intermediate member, said clamping plates bearing at one end on the intermediate member as a fulcrum, and means on the screw member for engaging 65 the clamping plates near the other end, independently of each other to form independent wire clamps.

2. A connector comprising an intermediate member, a screw member extending 70 therethrough, clamping plates mounted on the screw member on opposite sides of the intermediate member and bearing at one edge on the intermediate member as a fulcrum, and means on the screw member engaging the clamping plates near the opposite edge independently of each other to form 75 independent clamps.

3. A connector of the character set forth comprising an intermediate member, clamping members on opposite sides thereof bearing thereagainst near one edge only thereof, and means for forcing the said clamping members toward the said intermediate member independently of each other to form 80 independent clamps.

4. A connector of the character set forth comprising an intermediate member, clamping members on opposite sides thereof fulcrumed near their edges, and means for 85 forcing the said clamping members toward the said intermediate member independently of each other to form independent clamps.

5. A connector of the character set forth comprising an intermediate member, clamping portions on opposite sides of the said intermediate member, said clamping portions being yieldably detained at portions thereof, and means for forcing the said clamping portions toward the said intermediate 95 member independently of each other to 100 form independent clamps.

As inventor of the foregoing I hereunto subscribe my name this 26th day of November, 1906.

FREDERICK R. PARKER.
